CLAIM

The ornamental design for a protection cover for scooter, as shown and described.

DESCRIPTION

1. Protection cover for scooter

1.1 is a front elevation view of a protection cover for scooter showing my new design;

1.2 is a rear elevation view thereof;

1.3 is a left side elevation view thereof;

1.4 is a right side elevation view thereof;

1.5 is a top plan view thereof;

1.6 is a bottom plan view thereof; and

1.7 is a front and left side perspective view thereof.

The broken lines shown in the drawings illustrate portions of the protection cover for scooter that form no part of the claimed design.

1 Claim, 7 Drawing Sheets
